UNITED STATES PATENT OFFICE

2,413,031

CONTROL DEVICE

John H. Murch, East Orange, N. J., assignor to
 American Can Company, New York, N. Y., a
 corporation of New Jersey

Application December 14, 1943, Serial No. 514,253

5 Claims. (Cl. 93—49)

1

The present invention relates to a machine for making containers or can bodies from flat blanks or sheets and has particular reference to devices for controlling the actuation of the machine in accordance with the bringing together of marginal edge portions of the blanks or sheets to form side seams for the bodies. This is an improvement on the can body maker disclosed in United States Patent 2,169,311, issued August 15, 1939, to M. E. Widell.

In the manufacture of container bodies made from fibre or the like sheet material, a blank of the fibre stock is usually folded around a forming mandrel or horn to give the finished body its proper shape. When the body is to be rectangular in cross section, a rectangular shaped horn is used.

The folding of the blank around such a rectangular horn is usually effected in two steps. In the first step the blank is folded into a U-shape, thus forming three sides of the body. In the second step the fourth side of the body is formed by folding over into overlapping relation, the upper portions of the two upstanding legs of the blank. This second folding operation is usually performed by wing type fingers or slides which when operating at high speeds sometimes crumple the body material so that it becomes jammed on the forming horn and thus prevents further forming operations until the jammed condition is removed.

The instant invention contemplates providing an electric control device which operates to stop the machine when such a jam occurs.

An object of the invention is the provision in a container body making machine having movable folding fingers, of control devices which operate to stop the machine when a container body at the folding station becomes jammed so that other bodies moving as in a continuous procession through the machine will be prevented from becoming involved thus preventing serious damage to the machine.

Another object is the provision of such control devices which include electro-mechanical elements for stopping the machine.

Numerous other objects and advantages of the invention will be apparent as it is better understood from the following description, which, taken in connection with the accompanying drawings, discloses a preferred embodiment thereof.

Referring to the drawings:

Figure 1 is a transverse view of a can body making machine embodying the present invention, the view including a wiring diagram of electric control apparatus used in the machine;

2

Fig. 2 is an enlarged sectional view of a control device shown in Fig. 1, the view being taken substantially along the broken lines 2—2 in that figure, with parts broken away;

5 Fig. 3 is an enlarged face view of the control device shown in Fig. 1 with parts shown in a different position; and

10 Fig. 4 is a sectional view of the machine shown in Fig. 1, the view being taken substantially along the line 4—4 in that figure, with parts broken away.

As a preferred embodiment of the present invention the drawings illustrate control devices A (Fig. 1) located at a container body folding station B in a fibre container body making machine such as is described fully in the Widell patent hereinbefore mentioned. These devices are effective for stopping the machine in the event of a jam, during the folding of partially formed U-shaped container bodies C into square or rectangular shaped tubular bodies, while they are advanced along a forming mandrel or horn 11.

The body forming horn extends longitudinally of the machine and is supported in the usual manner above a vertical frame 12, carried on a machine base 13. The horn is disposed between side brackets 14 which keep the upstanding sides (indicated by the letters D and E) of the U-shaped partially formed bodies, in an upright position.

30 These brackets are secured to the top of the frame 12.

In order to incorporate the upstanding sides D, E of a partially formed body, into a side wall of the body, movable folding wings or fingers 15 are provided. These fingers move in from opposite sides of the horn 11 and fold the extended sides D and E inwardly and downwardly against the top of the horn in overlapping relation. The overlapped flaps thereafter are united in the usual manner with a bonding agent of adhesive between them and thus form the fourth wall or side of the container body.

Each movable finger 15 is secured to the upper end of a vertically disposed bell crank 16. There are two such bell cranks, one on each side of the horn 11 and these are carried on pivot studs 17 secured in the frame 12 at places below the horn (Fig. 1).

The bell cranks 16 are operated by vertical actuating links 18 which are connected at their upper ends to short horizontal arms 22 of the bell cranks. The links 18 are connected at their lower ends to actuating members or rocker levers 23 which are loosely mounted on pivot studs 24 threadedly or otherwise secured in the frame 12.

There are two such actuating members, one for each bell crank 16.

The actuating members 23 comprise a part of each control device A. Two such control devices are used in the instant invention, one for each folding wing 15. Each of the actuating members 23 is operated through its control device by a vertically disposed driving member or cam lever 25 which is loosely mounted on each of the pivot studs 24, adjacent the rocker levers 23.

The driving members 25 are rocked through a working stroke and thence through a return stroke by electro-mechanical machine operating means. These means include a cam roller 26 carried on the lower end of each of the two driving members 25 and which operates in a cam groove 27 formed in one of a pair of rotatable drum cams 28. These cams are mounted in spaced relation on a machine drive shaft 32 journaled in bearings 33 in the frame 12. The shaft 32 is rotated through a gear 34 mounted on one end of the shaft, and in mesh with and driven by a motor pinion 35 of an electric motor 36.

The actuating member 23 and the driving member 25 of each control device A (Figs. 2 and 3) are tied together by a yieldable connection so that both members normally operate as a unit. Each yieldable connection includes a pair of cooperating lugs 37, 38 formed respectively on the members 23, 25. The lugs of each pair normally are held together in operating engagement by a compression spring 42. This spring surrounds a bolt 43 which is threaded into one of the lugs and extends through a slot in the other. Locknuts on the outer end of the bolt hold the spring in place.

Hence as a driving lever 25 is rocked through a working stroke by its cam 28 the resulting action is imparted through the spring 42 to the adjacent actuating member 23 to its link 18 and connecting bell crank 16 and to the folding finger 15 carried thereby. This action results in the inward movement of the movable finger 15.

The cams 28 are timed to actuate both folding fingers 15 at the same time but one finger is caused to move just a little behind the other in order to effect a proper overlapping of the flaps of the container body. In the event of a jam, while folding one or the other of the flaps D, E of a container body, the jammed finger 15 will stop moving and its associated spring 42 will yield. This permits the associated driving member 25 to continue its movement which now takes place relative to the held member 23 (Fig. 3).

Provision is made under such conditions for stopping the machine so that the jammed container body may be removed. For this purpose slidable stop elements 44 (Figs. 2 and 3) are employed. There are two of these stop elements, one for each control device A and they are carried in upper arm sections 45 of each of the actuating members 23 and are retained in place by blocks 46 secured to the arm sections.

The lower end of each stop element 44 is formed with a foot 47 having a detent 48 which normally is engaged within a notch 49 formed in a curved top or cam surface 50 of a boss 51 formed on the driving member 25. A compression spring 52 interposed between the block 46 and the foot 47 of each stop element keeps the detent 48 yieldably in place in its notch 49 during normal operations of the machine.

The upper end of each stop element 44 is formed with an enlarged head 55 having a curved top surface which lightly engages against a movable element 56 of a normally closed electric stop

switch 57. There are two of these switches, one for each control device A and they are secured to the machine side frames 12. The curved surface of the enlarged heads of the stop elements slide back and forth across the outer end of the switch elements without actuating the elements, as the driving members 25 rock back and forth during normal operation of the machine.

The two electric stop switches 57 are connected in series by a wire 58 which forms part of an electric circuit connecting with the electric motor 36 hereinbefore mentioned. One of the switches is also connected by a wire 63 to the motor. The other switch is connected by a wire 64 to a suitable source of electric energy, such as a generator F. The generator in turn is connected by a wire 65 to one side of a service switch 66. The opposite side of this switch is connected by a wire 67 to the electric motor 36.

Hence when the service switch 66 is closed, electric energy from the generator F flows through the circuit, including the two normally closed stop switches 57 and thereby excites the motor 36 to keep the machine in normal operation. However, when a jam occurs in the machine and brings about the relative movement between the actuating member 23 and the driving member 25 of the control device A associated with the jammed forming wing 15 as hereinbefore mentioned, the detent 48 is forced upwardly out of its notch 49 and rides up on the top of the curved cam surface 50 of the driving member lug 51. This action lifts stop element 44 against the movable element 56 of the adjacent electric stop switch 57 and thereby opens the switch.

Opening of either one of the stop switches 57 in this manner breaks the motor circuit and thus stops the machine. When the jammed container body has been removed from the horn 11, the forming wing or wings will again function properly and the machine may then be turned over manually or be "jogged" into starting position by electric starting devices or the like to re-seat the dislocated detent 48. Re-seating of the detent will close the associated stop switch 57 and thereby re-establish the motor circuit for the resumption of the normal operation of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a container body forming machine, the combination of a horn, a movable finger for bending a portion of a container body blank on said horn, an actuating member for moving said finger, a driving member resiliently connected with said actuating member for operating it, said driving member being resiliently movable relative to said actuating member only when a body on said horn becomes jammed and stops further movement of said finger, machine operating means for said driving member, a stop element carried on one of said members and engageable with the other member and slidably movable by the latter when the members shift relative to each other, and means operable by said stop element when it shifts to stop said machine operating means.

2. In a container body forming machine, the combination of a horn, a movable finger for bending a portion of a container body blank over said horn, an actuating member for moving said finger, a driving member resiliently connected with said actuating member for operating it, said driving member being resiliently movable relative to said actuating member only when a body on said horn becomes jammed and stops the movement of said finger, electro-mechanical operating means for said driving member, a stop element slidably mounted on one of said members and resiliently engageable with the other member and slidably movable by the latter when the members shift relative to each other, and electric means operable by said stop element when the latter slidably shifts to stop said electro-mechanical operating means.

3. In a container body forming machine, the combination of a horn, a movable finger for wrapping a portion of a container body blank around said horn, a pivotally mounted actuating lever for moving said finger, a driving lever pivotally mounted adjacent said actuating lever and resiliently connected thereto for operating the latter, said driving lever being movable resiliently relative to said actuating lever only when a body on said horn becomes jammed and stops the movement of said finger, machine operating means for said driving lever, a stop element carried on one of said levers and engageable against a cam surface on the other of said levers and slidably movable by said cam surface when the levers shift relative to each other, and means operable by said stop element when the latter slidably moves to stop said machine operating means.

4. In a container body forming machine, the combination of a horn, a movable finger for wrapping a portion of a container body blank around said horn, a pivotally mounted actuating lever for moving said finger, a driving lever pivotally mounted adjacent said actuating lever and resiliently connected thereto for operating the

same, said driving lever being movable relative to said actuating lever only when a body on said horn becomes jammed and stops the movement of said finger, machine operating means for said driving lever, a slidable stop element carried on one of said levers and having a detent engageable in a notch formed in a cam surface on the other of said levers, spring means for normally holding said detent in its said notch to restrain movement of said stop element, said stop element being bodily slidably movable by said cam surface when said actuating and driving levers shift relative to each other, an electric switch engageable by said stop element and operable thereby when the stop element slidably moves relative to its carrying lever, and electric means engageable and operable by said electric switch for stopping said machine operating means.

5. In a container body forming machine, the combination of a horn, a plurality of movable fingers for wrapping portions of a container body blank around said horn, an actuating member for each of said fingers for moving the same, a driving member for each of said actuating members and resiliently connected with said actuating members for operating the latter, a said driving member for a given finger being movable relative to a said actuating member for the finger only when a body on said horn becomes jammed and stops movement of said finger, machine operating means for said driving members, a stop element carried on each of said actuating members and engageable with its said driving member and bodily movable by said driving member when the latter shifts relative to its associated actuating member, an electric stop switch disposed adjacent each of said actuating members and operable by the stop element of said actuating member when the latter slidably moves relative to its driving member, and electric means operable by any one of said electric switches for stopping said machine operating means.

JOHN H. MURCH.
